UNITED STATES PATENT OFFICE.

CECIL H. BOYULS, OF LOUISVILLE, KENTUCKY.

SHIRT BOSOM AND BODY MACHINE.

1,357,218.

Specification of Letters Patent. Patented Nov. 2, 1920.

Application filed May 11, 1920. Serial No. 880,488.

To all whom it may concern:

Be it known that I, CECIL H. BOYULS, a citizen of the United States, residing at Louisville, county of Jefferson, and State 5 of Kentucky, have invented a new and useful Shirt Bosom and Body Machine, of which the following is a specification.

This invention relates to machines adapted to iron the bosoms and bodies of shirts 10 at one operation.

An object of this invention is to provide a machine wherewith the bosom and the body of a shirt may both be ironed at the same time.

15 Another object is to provide a machine as characterized having a shaped heated form having expansible members about which a shirt may be placed and the members then expanded, thereby distending the body of 20 the shirt so that all wrinkles are removed.

A further object is the provision of a machine as characterized having a heated form over which a shirt may be drawn, and having means associated therewith whereby 25 the tails of the shirt may be smoothed out and maintained in contact with the form.

With the foregoing and other objects in view, the invention consists of the novel construction and arrangement of parts illustrated in the accompanying drawings, comprising 5 sheets, which form a part of this specification, wherein is set forth an embodiment of the invention, but it is to be understood that such changes and modifications 35 may be resorted to as come within the scope of the appended claims.

In the drawing, wherein similar reference characters designate like parts in the several views, Figure 1, is a front elevation 40 of an embodiment of the invention, showing the wings on one form as closed and on the other form as opened out: Fig. 2, a top plan view of same: Fig. 3, side elevation with parts broken away: Fig. 4, a section on line 45 4-4 of Fig. 3, showing the apron as open, in full lines and closed in dotted lines; Fig. 5, a central longitudinal section through a pedestal and horn, with some parts broken away and others omitted: Fig. 6, a section on line 50 6-6 of Fig. 5: Fig. 7, a top plan view of the neck band holder: Fig. 8, a section on line 8-8 of Fig. 7: Fig. 9, a detached perspective view of bosom board: Fig. 10, front elevation partly in section of 55 the bosom iron operating mechanism: Fig. 11, central longitudinal section through

bosom iron, arm and shaft; and Fig. 12, a detached detail showing a shirt in position on a form.

The machine comprises a base —4— 60 adapted to be secured to a foundation, or floor by means of bolts passing through laterally extended lugs —11—. The base is preferably of cast iron, hollow, and is substantially T shaped in plan, comprising a 65 cross arm —12— and a stem —13—. A pedestal —15— erected on each end of the arm, is cast hollow and is provided with openings in its walls which serve to reduce the weight and to afford access to the interior thereof. A horn, or form —17— is attached to the upper end of each pedestal and extends rearward therefrom with a suitable upward inclination. The horn is a hollow casting, having thick walls to withstand 70 the steam pressure and to hold heat, and is of such length as to permit a shirt of maximum length to be placed thereon and its breadth is greater than its thickness, its dimensions being such as to receive a shirt of 75 minimum size. A transverse section of the horn would be substantially a rhomb-ovate, or rhomboid with the outer angle —18— rounded. The upper end —19— of the horn is contoured to conform to the shoulders 80 and yoke of a shirt when it is positioned thereon for ironing. A recess —20— is provided in the upper surface of the horn near its upper end—within which a bosom board —21— is removably secured. The bosom 85 board is a hollow casting provided with a plurality of perforations through its top, and is connected with a suitable source of air under pressure, by means of a pipe —22— which lies in a groove —23— in the top of the horn. A pair of latch bars —24— pivoted at —25— on the ends of the bosom board, provides means whereby to fasten a suitable fabric —26— across the top of the board to serve as a pad. A neck band positioned on the bosom board near its upper end comprises a fixed semi-circular part —27— and a movable complementary part —28—. The movable part is carried by a tongue —29—, which is provided with rack 100 teeth —30— and which is adapted to slide in guide members —31— secured to the bosom board. A hand lever —32— fulcrumed in ears —33— on the guides, is provided with teeth —34— which are operatively engaged with those in the tongues 29, whereby the movable part of the band may 105 110

be moved to or from the fixed part, to accommodate the collar bands of different sized shirts. The fixed part is provided with a vertical slot —35— to receive the 5— collar button —36— which connects the ends of the band of a shirt. A pair of wings —40—, preferably formed of sheet metal, are so shaped that when in normal, *i. e.*, closed position, they envelop substantially 10 all of the horn, the bosom board excepted, and are heated by contact therewith. The wings are supported and guided in an opening, or spreading movement, by means of two pairs of rods —41— pivotally connected therewith at —42 43—, in the apex of the 15 angle, a spaced distance respectively from the upper and lower end thereof. The rods 41, are slidably disposed in bores —44— extended into the sides of the horn. A bar 20 —46— slidably disposed in ways —47—, centrally longitudinal of the form is adapted to be actuated by means of a lever —48— with which it is operatively connected. The lever 48, is mounted upon the pedestal and is adapted to be held in adjusted position 25 by means of a latch —49— which is engaged with a quadrant —50—. A pair of arms —51— are pivotally connected respectively with the bar 46 and with the 30 respective wings. The arrangement is such that when the lever is pushed in, the wings will be pushed outward away from the horn, and when the lever is drawn back, the wings will be drawn back into contact with 35 the horn. The sliding bar and arms lie below the surface of the horn and are covered by means of a plate —52—, the horn and associated wings comprise a form over which a shirt may be drawn. A bracket 40 —55— secured to the pedestal, a spaced distance below the horn, has an arm —56— which extends rearward therefrom in a plane substantially parallel with the horn and at its upper end supports a pan —57— so positioned as to catch and hold the depending 45 sleeves of a shirt when it is placed on the form. The arm 56, of the bracket is provided with longitudinal slot —58—. A plate —59— slidably positioned on the arm 50 is guided in its travel by means of a rib —60— fitted in the slot. A plate —61— secured to the rib and bearing on the underside of the arm holds the plate in place. A pair of arms —65— are pivotally mounted 55 upon ears —66— positioned on the upper, end of the plate at the outer edges thereof. The arms each comprise a long angular member having a bend —67— and a short member —68—. A rod —69— is secured to 60 the outer end of each of the angular members. The rods lie parallel with the form and are of such length that they reach from the lower end of the bosom board to the point to which the longest shirt will come. 65 A web —70— of suitable fabric, such as canvas is attached at its ends to the rods and constitutes an apron which is of such length as to be drawn tightly about the form when the arms are actuated. A pair of links —71— are connected respectively 70 to the short members 68 of the arms 65, and to a link —72—, which in turn is pivotally connected to one end of a lever —73, which is fulcrumed intermediate its length in a lug —74— which depends from the plate 75 59, through the slot 58. A substantially L shaped hand lever —76— is fulcrumed near its angle, in a lug —77—, secured on the base of the pedestal. The end of the horizontal arm of the hand lever is connected 80 by means of a link —79— with the end of the lever 73. The arrangement is such that a pull on the vertical arm of the hand lever will cause the angular members of the arms 85 65, to close about the form, stretching the 85 apron tightly about the form. A rod —80— pivotally connected at —81— with the plate 59, has a lost motion connection with the hand lever 76, comprising a slot —82— in the rod, and a pin —83— on the lever. The 90 arrangement is such that just as the apron closes about the form, traction will be exerted on the plate 59, drawing it and the entire structure carried by it, toward the base 95 of the form, this movement being completed 95 just after the apron is drawn taut about the form, whereby a fabric, such as the tails of a shirt, disposed on or about the form, will be smoothed out and firmly contacted therewith. A pedestal —90— positioned on the 100 stem 13, of the base intermediate its length and midway between the two horns, is provided on its upper end with a journal box —91— in which a hollow shaft —92—, is journaled, which has a central passage 105 —93—. To the forward end of the shaft, an arm —94— is secured. To the outer end of the arm, a hollow iron —95— is secured, and a passage —96— in the arm connects the 110 passage in the shaft with the interior of the iron. The width and length of the iron is substantially the same as the bosom board, it having a concavity —97— at its rear end corresponding with the neck bands 115 on the boards. It is thicker at its forward end than at its rear end to correspond with the inclination of the horns in order that its opposite faces which are highly polished, may contact uniformly with the face of the bosom boards as it is moved from side 120 to side by rotation of the shaft. A sprocket wheel —100— is secured on the shaft in the rear of the journal box, a sprocket chain —102— is disposed thereon and depends therefrom. The ends of the sprocket chain 125 are connected to plunger rods —103— which extend downward into cylinders —104— positioned in a chamber —105—, in the rear end of the base. A pump —106— likewise positioned in said chamber is opera- 130

tively connected with suitable motive means such as an electric motor —107— located on top of the chamber. A pipe —108— leads from the pump to an air chamber —109—.

5 A delivery pipe —110— leads from the air chamber and risers —111— and —112— lead from the delivery pipe to a connection with the cylinders 104, at the upper ends thereof. A stand pipe —114— projecting from the 10 delivery pipe carries a pop valve —115— which may be regulated to permit the escape of fluid wherever the pressure exceeds a predetermined figure. Three way valves —116 15 and —117— are interposed respectively in the continuity of the risers and are connected by means of a rod —120— so that they may be actuated simultaneously. The arrangement is such that when one valve as 117, is set to permit fluid to enter the corresponding 20 cylinder, the other valve is set to allow fluid to escape from its corresponding cylinder through a discharge —118—. As fluid enters a cylinder, the plunger therein is forced down, and through the medium of the rod 25 103, and chain 102, the iron 95, is moved over and caused to contact with the bosom board, on the corresponding side of the machine, with a pressure proportional to that of the fluid, at the same time the plunger in 30 the other cylinder is drawn up forcing the fluid out of that cylinder. The rod 120, extends exterior of the chamber and is operatively connected with an arm —121— depending from a shaft —122— which extends 35 to the front end of the base, being mounted in bearings —123, 124— positioned respectively on the side of the chamber (Fig. 10) and on the arm of the base (Figs. 1 and 2). On the forward end of the rod 122 is a yoke 40 —125—, the respective ends of which are operatively connected by means of flexible connectors —126— with a short shaft —127— and a long shaft —128— which are journaled on the front side of the base. These 45 shafts are each provided with a pedal —129— conveniently located to be actuated by an operator. A pipe —130—, which serves to conduct steam from a suitable source of supply (not shown) enters the hollow shaft 92, through a stuffing box —131—, the steam flows through the passages 93 and 96, into the iron 95, heating it to a desired 50 temperature. A pipe —132— leads from the forward end of the shaft to a steam trap 55 —133— in the base and a pipe —134— leads forward from the trap to the branch pipes —135— which lead upward through the interior of the pedestals to connections with the horns and deliver steam thereinto.

60 Water of condensation flows from the iron, and from the horns through pipes 132 and 135 and 134, to the trap and from thence through a pipe —136— to any suitable point of disposal. An air pump —140— is connected with the motor and air therefrom 65 under pressure is led through a pipe —141— and its branches —142— to connections with the pipes 22, which lie in grooves in the upper sides of the horns and are connected to the bosom boards. Air escaping 70 through the perforations 21, in the bosom board, serves to keep the pad 26 (Fig. 5) dry, and air issuing through openings 75 —145— within the neck band serves to keep the handle 32 cool, so it can be handled. In 80 operation a shirt which had been dampened, and properly conditioned for ironing, the neck band having been ironed in a customary manner, and its ends fastened together by means of a collar button —85—, is drawn 85 down over the form by an operator, until its shoulders contact with an end of the form. Its collar band is then disposed about the band on the bosom board with the collar button engaged in the slot 35. The hand lever 85 32, is then actuated to move the complementary part backward whereby the shirt band is tautened, shifting of the shirt being thereby prevented. The shirt tails are then drawn 90 down and smoothed out, the back tail lying 90 on the apron. The two sides of shirt front diverge from the collar button downward, to an extent such that the bottoms on one side of the bosom lie clear of the other side, and the inner lower corners are engaged by 95 suitable clasps —146— on the ends of elastic members —147—. When the shirt is properly positioned on the form, the lever 48, is pushed inward, whereby through the medium of the bar 46, and arms 51, the 100 wings 40 are moved outward from the horn. The wings move in parallel lines until the upper ends thereof are stopped by contact with the shoulders of the shirt, when they are fully distended, then the lower ends continue the outward movement, pivoting on the connections 42, until the body of the shirt, which slopes from the shoulders downward, is distended. The lever 76 is then pulled outward, causing the apron 70, to be 105 drawn about the form smoothing out the shirt tails in contact with the horn and distended wings.

The operator then depresses the appropriate pedal thereby actuating the valves 115 116, 117, and causing the iron to be brought into contact with the bosom of the shirt just positioned. He then steps over to the reverse form, whereon there is a shirt which has just been ironed and moves the levers 76, 120 48, and 32 in the reverse direction to that just described, thereby withdrawing the apron, and retracting the wings and releasing the collar band, whereupon that shirt may be withdrawn from the form. The 125 body of the shirt having been, by the combined action of the wings and the apron, smoothly contracted, through out practi-

ally its entire extent — except the bosom and a narrow space thereabout, with the heated form, while damp, has been dried perfectly smooth, and the bosom has been suitably finished by pressure of the iron thereon. Another shirt is then placed on the form and the operations as described being repeated.

Having thus described my invention so that those skilled in the art pertaining thereto can make and use the same,

I claim:

1. In a machine as characterized, a form adapted to have a garment distended thereabout and expansible distending means associated with said form and adapted to distend said garment to cause it to contact with the form and with the distending means.
2. In a machine as characterized, a form adapted to have a garment disposed thereabout, and means associated with said form and adapted to distend said garment to cause it to be disposed about one portion of the form, and other means to engage the garment to cause it to contact with the form and distending means.
3. In a device as characterized, a form, means for heating said form, wings normally closed about and heated by the form and means for moving said wings laterally in planes parallel with the form.
4. In a shirt ironing machine, a heated form, wings normally closed thereabout and adapted to have a shirt disposed thereover, and means operable to move said wings outward from the form thereby distending the shirt and stretching it tightly thereabout.
5. In a shirt ironing machine, a heated form, wings normally closed thereabout, means operable to move said wings outward from said form thereby distending the body of the shirt disposed thereabout, and a web adapted to be drawn about the form and

the wings to smooth the tails of the shirt out in contact therewith.

6. In a shirt bosom and body ironing machine, a plurality of forms, an iron, means for heating said iron and the forms, means for contacting the iron alternately with the forms, a web associated with each of the forms and means operable to adjust said web about a form to cause a fabric placed thereon to contact smoothly therewith.

7. In a shirt bosom and body ironing machine, a plurality of forms, an iron, means for heating said iron and the forms, means for contacting the iron alternately with the forms, wings normally closed about said forms, means associated with the respective forms operable to move said wings outward from the forms and a web associated with each of the forms and means operable to adjust said web about the associated form to cause a fabric placed thereon to contact smoothly therewith.

8. In a machine as characterized, a form, supporting members associated with and extensible from said form, wings conformable with the form carried by said members, a bar slidably associated with the form, arms pivotally connected respectively with the wings and with the bar whereby movement of the bar moves the wings from and toward the form, means for actuating the bar, levers pivotally mounted below the form the long arms whereof are so contoured as to extend about the respective sides of the form the terminals of said levers meeting over the form centrally and in proximity to the surface thereof, a web attached to the terminals of said arms adapted to be drawn about the form by the action of said levers, and means for actuating the levers.

CECIL H. BOYULS.
